2,191,062

ORTHO- AND PARA - NITROPHENYL - TRI-FLUOROMETHYL - SULPHOXIDES, OXIDA-TION PRODUCTS THEREOF, AND PROC-ESS OF PREPARING THE SAME

Willy Schumacher, Otto Scherer, and Fritz Müller, Frankfort-on-the-Main, Germany, as-signors to General Aniline & Film Corporation, a corporation of Delaware

No Drawing. Application October 5, 1938, Serial No. 238,474. In Germany October 5, 1937

5 Claims. (Cl. 260—607)

The present invention relates to ortho- and para- nitrophenyl - trifluoromethyl - sulphones, oxidation products thereof and to a process of preparing the same; more particularly, it relates to compounds of the following general formula:

15

wherein the nitro-group stands in one of the positions ortho and para to the group XCF₃, X stands for SO or SO₂, Y₁ stands for halogen or alkyl, and Y₂ for hydrogen or halogen.

According to the statements in "Chemisches Centralblatt," 1925 (2), page 1671, the nitration of methyl-phenyl-sulphone leads only to the formation of meta-derivatives. It could not be found that the presence of the methane sulphonyl group determined substitution in para-position. A constitution similar to that of the methyl-phenyl-sulphone has also the trifluoromethyl-phenyl-sulphone of the formula

25

Consequently, the nitration of this compound also occurs only in meta-position, as expected. Ortho- and para-nitrophenyl trifluoromethyl-sulphones cannot be obtained in this manner.

30

We have found that ortho- and para-nitro-derivatives of trifluoromethyl-phenyl-sulphones are obtainable by causing nitric acid to act in the presence of sulphuric acid upon the trifluoromethyl-phenyl-sulphides obtainable as described in U. S. Patent No. 2,108,606 and oxidizing the nitrophenyl-trifluoromethyl-sulphoxides so obtained. Since the trifluoromethyl-phenyl-sulphides, under the said conditions, are first oxidized to form the trifluoromethyl-phenyl sulphoxides and the latter are then nitrated in the second phase to the nitrophenyl-trifluoromethyl-sulphoxides, there may also be used as parent material for the manufacture of the ortho- and para-

5

nitrophenyl-trifluoromethyl-sulphones the trifluoromethyl-phenyl-sulphoxides obtainable in a manner similar to that described in "Chemisches Centralblatt," 1927 (1), page 1821, by causing nitric acid to act upon trifluoromethyl-phenyl sulphones. The nitro-group enters always in ortho- or para-position to the SO₂CF₃-group.

10

It is surprising that the action of nitric acid in the presence of sulphuric acid upon the trifluoromethyl-phenyl-sulphides or trifluoromethyl-phenyl-sulphoxides is so smooth and uniform, since by the action of nitric acid upon para-bromothio-anisol and thio-anisol only the corresponding sulphoxides have been obtained, but no nitrated sulphoxides (cf. Chemisches Centralblatt, 1927 (1), page 1822).

15

20

The simultaneous oxidation and nitration of the trifluoromethyl-phenyl-sulphides or the nitration of the trifluoromethyl-phenyl-sulphoxides by means of nitric acid in the presence of sulphuric acid occurs very smoothly, and the nitrophenyl-trifluoromethyl-sulphoxides are obtained with very good yields. They may easily be oxidized with the usual oxidizing agents to form the corresponding nitrophenyl trifluoromethyl sulphones which are valuable parent materials, for instance, for the manufacture of dyestuffs or pharmaceutical products.

25

30

The following examples serve to illustrate the invention, but they are not intended to limit it thereto; the parts are by weight unless otherwise stated:

35

40

45

1. 25 parts of 2,4-dichlorophenyl-1-trifluoromethyl-sulphide are caused to run, while stirring, into 75 parts by volume of a mixture consisting of about 30 per cent. of pure nitric acid and about 70 per cent. of sulphuric acid monohydrate and heated on the steam bath at about 60° C. to 70° C. Stirring is continued for a short time at 70° C. to 80° C. and the whole is then poured on ice. The 2,4-dichloro-6-nitrophenyl-1-trifluoromethyl-sulphoxide of the formula

which has separated is filtered with suction and washed. It is obtained with a nearly quantitative yield in the form of a feebly yellow powder. By recrystallization, for instance, from trichloroethylene, beautiful crystals are obtained which melt at 100° C.

31 parts of 2,4-dichloro-6-nitrophenyl-1-trifluoromethyl-sulphoxide are dissolved in 100 to 150 parts by volume of glacial acetic acid. Into 10 this solution there are introduced by portions at about 40° C., while stirring, about 10 parts of chromic anhydride. When the introduction is finished, the whole is heated for 1/2 to 1 hour at 70° C. to 80° C. and then diluted with water. 15 The 2,4-dichloro-6-nitrophenyl-1-trifluoromethyl-sulphone of the formula

25 which has separated is filtered with suction. After recrystallization, for instance, from benzine, it is obtained in the form of yellow crystals melting at 76° C. The yield obtained is nearly quantitative.

30 2. At 70° C. to 80° C., 74 parts of 3,4-dichlorophenyl-1-trifluoromethyl-sulphide are run, while stirring, into 200 parts by volume of a mixture consisting of about 90 per cent of pure nitric acid and about 10 per cent of sulphuric acid monohydrate. Stirring is continued for 1 to 2 hours at 70° C. to 80° C. and the whole is then poured on ice. The 3,4-dichloro-6-nitrophenyl-1-trifluoromethyl-sulphoxide which has separated is 35 filtered with suction and washed. It is obtained with a very good yield in the form of a yellow powder and after recrystallization, for instance from alcohol, it forms yellow crystals, melting at 100° C. The compound is oxidized, as indicated in Example 1, to form the 3,4-dichloro-6-nitrophenyl-1-trifluoromethyl-sulphone, melting at 40 72° C. to 73° C.

45 3. In a manner quite similar to that described in Example 1, there is obtained from 2-chlorophenyl-1-trifluoromethyl-sulphide with a good yield the 2-chloro-4-nitrophenyl-1-trifluoromethyl-sulphoxide which melts at 51° C. and is transformed by oxidation into the corresponding sulphone melting at 46° C.

50 Instead of 2-chlorophenyl-1-trifluoromethyl-sulphide there may also be used other halogen-substituted products of phenyltrifluoromethyl-sulphide, for instance, the meta- or para-chloro-derivative, mono-bromo-derivatives or the like.

55 4. At 50° C. to 60° C., 124 parts of 2,5-dichlorophenyl-1-trifluoromethyl-sulphide are run into 60 250 parts by volume of a mixture consisting of 90 per cent of pure nitric acid and 10 per cent of sulphuric acid monohydrate. The product is worked up as described in Example 1. The 2,5-dichloro-4-nitrophenyl-1-trifluoromethyl-sulphoxide melts at 99° C. to 100° C. and the sulphone obtainable therefrom by oxidation with a nearly quantitative yield melts at 60° C. In this case 65 too there may be used instead of 2,5-dichlorophenyl-1-trifluoromethyl-sulphide the corresponding bromo-compound.

70 5. In a manner similar to that indicated in Example 1 or 2 there is obtained from 4-methylphenyl-1-trifluoromethyl-sulphide the 4-methyl-

2-nitrophenyl-1-trifluoromethyl-sulphoxide which, after recrystallization, for instance, from benzine, form feebly yellow needles melting at 84° C. The 4-methyl-2-nitrophenyl-1-trifluoromethyl-sulphone obtainable therefrom by oxidation melts at 56° C.

75 6. 26.3 parts of 2,4-dichloro-phenyl-1-trifluoromethyl-sulphoxide melting at 60° C., are introduced at 10° C. to 15° C. while stirring, into 10 50 parts by volume of a mixture of 90 per cent of pure nitric acid and 10 per cent of sulphuric acid monohydrate. Stirring is continued for about 2 to 3 hours at 10° C. to 15° C. and the whole is then poured on ice. The 2,4-dichloro-6-nitrophenyl-1-trifluoromethyl-sulphoxide is obtained 15 with a quantitative yield. It is identical with the compound described in Example 1 and melts at 100° C.

20 Instead of the mixture of nitric acid and sulphuric acid mentioned in the examples there may, of course, also be used mixtures of these acids in all other proportions; furthermore, there may be used for the oxidation of the sulphones to the corresponding sulphones potassium permanganate, bichromate and sulphuric acid, permonosulphuric acid, or the like, instead of chromic acid.

25 We claim:

30 1. The process which comprises causing nitric acid to act in the presence of sulphuric acid at a temperature below 100° C. upon a compound of the following general formula:

40 whereon X stands for one of the group consisting of S and SO, Y_1 stands for a member of the group consisting of halogen and methyl and Y_2 for a member of the group consisting of hydrogen and halogen.

45 2. The process which comprises causing nitric acid to act in the presence of sulphuric acid at a temperature below 100° C. upon a compound of the following general formula:

55 whereon X stands for one of the group consisting of S and SO, Y_1 stands for a member of the group consisting of halogen and methyl and Y_2 for a member of the group consisting of hydrogen and halogen, and oxidizing the nitrophenyl-trifluoromethyl-sulphides thus obtained.

60 3. The compounds of the following general formula:

70 whereon the nitro-group stands in one of the positions ortho and para to the SO_2CF_3 group, Y_1 stands for a member of the group consisting of

halogen and methyl and Y_2 for a member of the group consisting of hydrogen and halogen, being yellow-colored crystallized products.

4. The compound of the following formula:

5

being a yellow-colored crystallized product which melts at 99° C. to 100° C.

5. The compound of the following formula:

10 forming, when recrystallized from benzine, feebly yellow needles melting at 84° C.
